UNITED STATES PATENT OFFICE.

JOSEPH WESTON COYLE, OF HARRINGAY, ENGLAND.

MACHINE FOR MAKING RECEPTACLES.

1,112,121.

Specification of Letters Patent. Patented Sept. 29, 1914.

Application filed June 30, 1913. Serial No. 776,546.

To all whom it may concern:

Be it known that I, JOSEPH WESTON COYLE, a subject of the King of Great Britain, residing at 50 Burgoyne road, Harringay, London, England, have invented new and useful Improvements in Machines for Making Receptacles, of which the following is a specification.

My invention relates to folding and gumming mechanism for use in machines for the manufacture of cartons, paper boxes, bags and the like, the invention being specially applicable to machines of the kind described in the specification of my former application Serial No. 757997 provided with two sets of folding and gumming mechanism to which the sheets of material to be folded are fed alternately by a single feed mechanism, but also applicable for use in machines where the feed is otherwise effected, the chief object of my invention being to provide a folding and gumming mechanism which shall operate in such a manner that a powder-proof box, carton or the like shall be obtained.

The improved mechanism comprises a plunger which reciprocates vertically in a forming slot or channel beneath it, the said slot having arranged in conjunction with it combined folding and gumming rollers carried by a bell-crank lever which is operated in such a manner as to cause the rollers to partially fold the blank, on one side of the plunger and apply gum, the final folding being effected by fixed fingers and hinged leaves arranged adjacent to the folding channel. Spring devices are also arranged in conjunction with the folding channel for retaining the folded carton when the plunger again rises, and also for pushing in the sides of the folded carton when removed from the plunger so as to prevent the next formed carton from being telescoped into it.

To enable my invention to be fully understood, I will describe the same by reference to the accompanying drawings, in which:—

Figure 1 is a front view of so much of a box or carton making machine as is necessary to illustrate my invention. Fig. 2 is a plan, and Fig. 3 an end view of the same. Fig. 4 is a vertical section on the line 4, 4, Fig. 1. Fig. 5 is a horizontal section on the line 5, 5, Fig. 1, showing a part of the folding mechanism. Fig. 6 is a sec-

tional plan of a part of the gumming mechanism. Figs. 7, 8 and 9 are perspective views illustrating different stages of the operation of the gumming and folding a carton. Fig. 10 is a perspective view of a finished carton. Figs. 11 and 12 are views of opposite sides of a folded carton opened out in order to show the position of the folds and the positions in which the gum is applied. Figs. 13 and 14 are views similar to Figs. 1 and 3 illustrating a modification.

a indicates one end of the frame of a machine of the kind described in the specification of my said former application Serial No. 757997 and *b* the table on to which the blanks to form the cartons or the like are fed, say through the medium of feed rollers *c*, *c*.

d is the plunger which effects the partial forming or folding and *e* the forming channel arranged beneath a slot *f* in the table through which slot the said plunger presses the blanks. The channel *e* is, as shown, formed between two plates *g*, *g*¹ which are secured to the frame *a* and to one another by the bolts *g*².

h is a tilting platform which is sometimes used and which is mounted upon the table *b* so that when lying in its horizontal position its upper surface is flush with the surface of the table and so that one end projects over the folding channel *e*, as clearly shown in Figs. 1 and 2.

i, *i* are the folding rollers and *i*¹, *i*¹ are flanges formed upon the said rollers and the peripheries of which form the gumming surfaces. These rollers are carried by the arms *j*, *j* of a bell-crank lever formed in duplicate and freely pivoted on a shaft *j*¹, the said levers having their arms *j*² connected by a tie-rod *j*³ so as to compel them to move in unison against the tension of a spring *j*⁴.

It will be understood that these duplicate bell-crank levers are mounted in such relation to one another that the distance between the opposed faces of the rollers *i*, *i* which they carry will correspond with the width of the plunger *d* plus the thickness of the material to be folded. This duplex bell-crank lever *j*, *j*² is operated through the medium of a trip-lever *k* pivoted at *k*¹ in the plate *g* so that one end projects into the forming channel *e* the other end of the said lever *k* being connected with the bell-crank lever by means

of a rod k^2 in such a manner that, when the projecting end or nose of the said trip-lever k is acted upon by the plunger d , it will be pushed down by the said plunger and cause 5 the bell-crank lever to rock upon its axis in order to bring the rollers i , from the position shown in full lines in Fig. 1 to that indicated by the dotted lines in the said figure.

10 At the sides of the channel e adjacent to the rollers i are arranged the finger-pieces l which coöperate with the said rollers to form the tucks in the bottom of the box, as hereinafter described, and below these finger-pieces again are arranged hinged leaves or plates m which, when the plunger has reached a certain point close against the latter to fold in certain of the flaps on the carton. These leaves are arranged in conjunction with springs which tend to close them against the plunger and are pulled away from the plunger at the desired moment by means of a cam n on the shaft of the machine from which the plunger is reciprocated, but which is not described or illustrated in the present specification as it forms no part of the present invention. The motion of this cam is transmitted to the leaves m through the medium of a lever n^0 25 and a piece n^1 of the well known "Bowden" wire, which is attached to a block n^2 having flexible connection n^3 , n^3 connected to the leaves. Where two sets of folding mechanism are employed as described in my said former application Serial No. 757,997 another lever n^0 and wire n^1 indicated by dotted lines in Fig. 1, are employed in conjunction with the cam n to operate the plates m of the additional folding mechanism.

30 o , o are gum font rollers which are attached to the shaft j^1 and the peripheries of which are grooved so that the gumming portions i^1 , i^1 of the rollers i , i can run in them; these font rollers can be rotated by any suitable means, for instance, through the medium of a chain p running upon a sprocket-wheel p^1 , on one of the shafts of the machine, which is alternately driven in opposite directions and synchronises with 35 the up and down movement of the plunger d . The chain p also passes around a sprocket wheel p^2 , on the shaft j^1 . Either of the wheels p^1 , p^2 is arranged as a free wheel, that is to say, it only drives in one direction 40 and runs free in the other direction the shaft j^1 being rotated in the downward movement of the plunger d . The gum is supplied to the font rollers o , o from fonts q , q in the form of boxes arranged in rubbing contact 45 with the peripheries of the wheel c , c , gum being supplied to these boxes from a tank through pipes such as q^1 .

50 In the operation of the machine the blank is fed on to the table b and brought to rest 55 with its center beneath the plunger d so that,

as the latter descends, the two ends of the blank will turn upward against the faces of the said plunger, as shown in Fig. 7 to form two flaps r , r^1 . As the plunger d moves downward the lower parts of the front flap r , come into contact with the gumming surfaces i^1 so that gum is applied as indicated at s , s , Fig. 7 to those parts of the flap to which the tucks hereinafter described formed at the bottom of the box are to be caused to adhere. The plunger having reached this position comes into contact with the projecting nose of the lever k and thereby oscillates the duplex bell-crank lever j , j^2 so that the folding rollers i come into contact with the lateral portions of the front flap r and turn them inward in contact with the sides of the said plunger, as shown in Fig. 8, the bottom tucks t being at the same time partially formed, and the gumming surfaces i^1 , i^1 brought into contact with the lateral portions of the back flap r^1 , while at the same time a little gum is applied on to the partially folded tucks, as indicated at s^1 . As during, the downward movement the partially folded tucks t , t come into contact with the fingers l , l they are turned upward against the gummed portions s , s as shown in Fig. 9. The downward movement of the plunger d continuing the lateral portions of the back flap r^1 are moved past the gumming rollers and are gummed as at s^2 , Fig. 9. This gumming having been completed the further downward movement of the plunger d brings the box or carton between the hinged leaves m , m which have previously been opened or turned back by the cam n , whereupon the said leaves are instantaneously closed to fold the said lateral portions of the back flap r^1 on to the previously folded lateral portions of the front flap r to complete the folding operation and to produce a box or carton of the shape shown in Fig. 10. Figs. 11 and 12 show clearly the folds indicated by dotted lines, which are put into the blank during the folding operation and the positions in which the gum is applied. As the plunger d reaches its extreme downward position, blade springs u arranged on the plates g , g^1 pass above the edges of the folded box into contact with the plunger, so that, as the plunger moves upward, they prevent the said box from moving with it. As the plunger leaves the carton or box other blade springs v , which were pressed into recesses in the plates g , g^1 by the downward movements of the plunger, spring inward and slightly push in the sides of the said carton or box, as indicated by the dotted lines in Fig. 10, so that when the bottom of the next folded carton comes into contact with it, the latter will be forced downward in the channel e without its being entered by the said next folded carton.

In the foregoing description I have re-

70

130

ferred to the use of the tilting table *h*. This tilting table, however, is not necessary when the cartons are made from a stiff paper. Where, however, a paper or material is being used which is flimsy and liable to fall over under its own weight when the flaps *r*, *r*¹ are being turned up by entering the slot *f* it is essential to keep the front flap *r* upright so as to insure the proper gumming 5 at the points *s*, *s*, this being effected by the said table. Without the use of this tilting table the weight of the projecting portion of the flap *r* above the table might have the effect of bending the paper so as to keep the 10 portions of the flap upon which the gum should be applied at *s*, *s* out of contact with the roller gumming surfaces *i*¹ at the required moment. The table *h* is provided with a spring *h*¹ to maintain it in its normal 15 position as shown.

w, *w* are bars arranged at the sides of the lower part of the channel *e* and designed to be heated in any suitable manner so as to dry the gum on the cartons as they are fed 20 downward in the said channel.

As in some cases the projection of the nose of the lever *h* for rocking the duplex lever might be objectionable I may modify the arrangement of this lever, that is to say, 25 instead of causing it to project into the channel *e* in which the folding is effected I may arrange it outside the channel, as shown in Figs. 13 and 14, and provide a supplementary plunger *d*¹ for making contact with the said lever, this supplementary plunger operating in the manner hereinbefore indicated at the required moment. As the spring *j*¹ in connection with the lever *k* in this arrangement is connected to the 30 frame *a* instead of to a part of the gum font support as in Figs. 1, 2 and 3 the fonts *c* may be connected by a cross channel.

Claims:

1. A machine for making receptacles comprising a forming channel, a plunger adapted to slide in said channel, folding and gumming devices normally outside of said channel, and means connected to said folding and gumming devices and extending 45 into said channel adapted to be engaged by said plunger to bring the folding and gumming devices into operative relation with said plunger.

2. In a machine for making receptacles, 50 wherein a reciprocating plunger cooperates with a forming channel, the combination with the said plunger, of rollers mounted upon an oscillating lever, each of said rollers having folding and gumming surfaces.

3. A receptacle making machine comprising a forming channel, a plunger adapted to slide in said channel, an oscillating lever, 55 rollers mounted upon said oscillating lever, each of said rollers having folding and gumming surfaces, and means connected to said

lever and extending into said channel adapted to be engaged by said plunger to operate said rollers.

4. A machine for making receptacles, comprising a forming channel, a plunger adapted to slide in said forming channel, an oscillating lever, combined folding and gumming rollers mounted on said lever, and means connected with said lever adapted to be engaged by said plunger to operate said 70 rollers.

5. A machine for making receptacles comprising a forming channel, a plunger adapted to slide in said channel, an oscillating lever, combined folding and gumming rollers mounted on said lever, means connected to said lever extending into said channel and adapted to be engaged by said plunger for moving the lever and rollers toward the plunger, and a spring for drawing the lever 80 away from said plunger.

6. A machine for making receptacles, comprising a forming channel, a plunger adapted to slide in said channel, rollers each of which have separate folding and gumming 90 surfaces adapted to fold and gum a blank upon said plunger, fingers for forming the bottom tucks, and hinged leaves for completing the folding.

7. A machine for making receptacles comprising a forming channel, a plunger adapted to slide in said channel, combined folding and gumming rollers adapted to fold and gum one side of a blank upon said plunger and gum the opposite side of said blank, 95 fingers located at the side of said channel and adapted to force the lateral lower edges of said blank upwardly, and hinged leaves adapted to be forced against the edges of the second named side of said blank to form 100 a receptacle.

8. A machine for making receptacles comprising a forming channel, a tilting table pivotally mounted at the mouth of said channel and adapted to bear against one 110 side of a blank in making a receptacle, a plunger adapted to slide in said channel, and rollers each of which have separate folding and gumming surfaces adapted to fold and gum the blank upon said plunger.

9. A machine for making receptacles comprising a frame, a forming channel provided in said frame, a plunger adapted to slide in said channel, bell crank levers pivotally mounted on said frame adjacent said forming channel, combined folding and gumming rollers mounted on one end of said levers, a nose piece pivotally mounted to said frame and extending into said channel, and a link provided between the bell 115 crank levers and said nose piece.

10. A machine for making receptacles comprising a frame, a forming channel provided in said frame, a plunger adapted to slide in said channel, oscillating levers piv- 120

totally mounted on said frame adjacent said channel, rollers having folding and gumming surfaces, a gum font and grooved wheels adapted to be rotated in said gum font, the gumming surfaces of said rollers being adapted to travel in the grooves in said grooved wheels.

11. A machine for making receptacles comprising a forming channel, a plunger adapted to slide in said channel, the blank for making the receptacle being adapted to

be forced into said channel by said plunger, oscillating levers, combined folding and gumming rollers mounted on said levers, and springs provided in said channel to 15 prevent the blank from being withdrawn by said plunger.

JOSEPH WESTON COYLE.
